UNITED STATES PATENT OFFICE.

WILFRED J. GLADUE, OF WOONSOCKET, RHODE ISLAND.

SHUTTLE AND METHOD OF MAKING SAME.

Application filed March 4, 1924. Serial No. 696,736.

To all whom it may concern:

Be it known that I, WILFRED J. GLADUE, a citizen of the United States, residing at Woonsocket, in the county of Providence and State of Rhode Island, have invented new and useful Improvements in Shuttles and Methods of Making Same, of which the following is a specification.

This invention relates to certain new and useful improvements in shuttles and method of making same, and the primary object thereof is to provide a shuttle the body of which is formed of fiber, thereby to economize in the cost of production, both as concerns the cost of material and the manufacture.

A further object of the invention is to provide a method of making the shuttles which can be easily and expeditiously practised.

Still further, the invention has for its object the provision of novel caps for the shuttle ends and means for attaching same in position.

The invention has still further and other objects, which will be later set forth and manifested in the course of the following description.

In the drawings:—

Figure 1, is a top plan view of the shuttle, partly broken away, constructed in accordance with the present invention;

Figure 2, is a side elevation of Figure 1;

Figure 3, is a top plan view of one of the end castings;

Figure 4, is a side elevation of Figure 3;

Figure 5, is an end elevation of Figure 4;

Figure 6, is a section on line 6—6 of Figure 1;

Figure 7, is a top plan view of the other end casting;

Figure 8, is a side elevation of Figure 7;

Figure 9, is an end elevation of Figure 8;

Figure 10, is a side elevation of one of the end caps, and

Figure 11, is an end elevation of Figure 10.

In proceeding in accordance with the present invention, a tube of fiber in what is generally termed its "green" or "wet" state is employed. A form is introduced into the tube interior, which includes end members of somewhat truncated cone formation, the end members being connected by a series of central or intermediate form members, the end and central or intermediate

form members having mitered joints. The outer ends or tips of the end form members have reduced or depressed portions corresponding in form to that of the metallic tips or caps 12, which latter are illustrated in Figures 10 and 11 of the drawings. The form composed of the end and intermediate members has an external shape corresponding to that which the finished shuttles is to possess. The green fiber is next subjected to pressure so as to compress or shape and cause same to conform to the shape of the form, which step results, in the shaping of the fiber ends with inwardly offset parts 70 forming depressed portions indicated at 6 in the drawings. The fiber is now dried or baked so as to cause same to become hard and maintain the shape imparted thereto by the form, following which the central top portion of the fiber is removed, as by cutting down to the form, to provide the usual bobbin-receiving cavity or chamber 7.

The several sections of the form are now removed and castings 8 and 8' positioned in the ends of the fiber body, the castings having cut-out end portions 9 and 9' which receive the depressed portions 6 occurring at the ends of the fiber body. These castings may be made of aluminum or other metal 85 and are provided with bores 10 the latter receiving metal threaded shanks 11 of the end caps 12. Nuts 13 are applied to the shanks 11 and are driven thereon so as to effect firm anchorage of the caps to the fiber body. The wings 14 of the end caps have their tips 15 deflected inwardly so as to be embedded in the fiber and be firmly anchored thereto. From the foregoing it will be noted that the ends of the fiber body are strengthened and reinforced both interiorly and exteriorly thereof, and are held against any tendency to move outwardly by the end caps which clamp the fiber tube ends against the interior castings.

The castings and end caps are additionally secured in place by cement.

The final step resides in applying linings or sections of bakelite or equivalent material 16, which latter are sprung into position in 105 the fiber body and are cemented to the side walls thereof.

The castings may be of any type desired to accommodate any desired type of bobbin mounting and the usual or any preferred 110 form of threading and delivery eyes.

Having thus described my invention what

I claim as new and desire to secure by Letters Patent is:—

1. In a shuttle, a tubular fiber body having tapered ends formed with inwardly offset parts forming external depressions, castings in the ends of the body having depressed parts to receive the said offset parts and having axial bores, end caps engaged over the ends of the fiber body and having wings received in said external depressions, the tips of the wings being deflected inwardly and embedded in the body, said caps having threaded shanks received in the casting bores, nuts in the castings engaged with the shanks to draw the caps and castings together, and linings in the body secured to the sides thereof. 50
2. In a shuttle, a tubular fiber body having tapered ends formed with inwardly offset parts forming external depressions, castings in the ends of the body having depressed parts to receive the said offset parts and having axial bores, end caps engaged over the ends of the fiber body and having wings received in said external depressions, said caps having threaded shanks received in the casting bores, and nuts on the shanks to draw the caps and castings together. 55
3. In a shuttle, a tubular fiber body having tapered ends, castings in the ends of the body, end caps fitted over said tapered ends of the body, and means to secure the caps and castings together and with parts of the ends of the body clamped therebetween. 60
4. In a shuttle, a tubular fiber body having tapered ends, castings in the ends of the body, end caps fitted over said tapered ends of the body, means to secure the caps and castings together and with parts of the ends of the body clamped therebetween, and lining members secured to the inner side faces of the body. 65
5. The herein-described method of making shuttles, which consists in placing a form on the interior of green tubular fiber stock, then in applying pressure to the stock to cause same to conform to the shape of the form, then in cutting away a part of the top of the stock to permit access to the core or form, then in hardening the stock, securing lining members to the inner side faces of the stock, and finally in applying interior castings and exterior end caps to the ends of the stock and securing said castings and caps together and in rigid relation to the stock. 70
6. The herein-described method of making shuttles, which consists in placing a form on the interior of green tubular fiber stock, then in applying pressure to the stock to cause same to conform to the shape of the form, then in cutting away a part of the top of the stock to permit access to the form, and then in hardening the stock. 75
7. The herein-described method of making shuttles, which consists in placing a form on the interior of green tubular fiber stock, then in applying pressure to the stock to cause same to conform to the shape of the form, then in cutting away a part of the top of the stock to permit access to the form, then in hardening the stock, and finally in securing lining members to the inner side faces of the stock. 80
8. The herein-described method of making shuttles, which consists in placing a form on the interior of the green tubular fiber stock, then in applying pressure to the stock to cause same to conform to the shape of the form, then in cutting away a part of the top of the stock to permit access to the form, then in hardening the stock, and in securing end caps to the ends of the stock. 85

In testimony whereof I have signed my name to this specification in the presence of two subscribing witnesses.

WILFRED J. GLADUE.
